ELECTRIC SWITCH GEAR

George Kiminster, Birmingham, England, assignor of one-half to Ega Electric Limited, Wednesbury, England

Application July 29, 1948, Serial No. 41,321
In Great Britain August 2, 1947

4 Claims. (Cl. 200—122)

1

This invention relates to electrical overload switches and is concerned with overload switches for operation in electrical circuits having a plurality of conducting leads in each of which the presence of an overload current is required to actuate the switch.

The invention is specifically concerned with electrical overload switches of this kind which comprise a plurality of bi-metal strips, one strip being associated with each of said conducting leads and being adapted to bend when subjected to temperature change, a plurality of heating windings one being associated with each strip and being secured in proximity to each strip so that a proportion of the heat developed in the winding is transmitted to the strip, overload switch contacts and an operating member common to all said bi-metal strips and having a lost motion connection with the free end of each strip, said operating member being supported so as to move the overload switch contacts relatively to each other when moved through the operation of one of said lost motion connections, the winding associated with each strip being adapted to carry a current varying with that in each of said respectively associated leads.

The object of the present invention is to provide a new or improved construction in which alternative overload settings are made available without adding to any appreciable extent to the complication and manufacturing cost of the device.

A specific embodiment of the present invention is illustrated in the accompanying drawings, wherein:

Figure 1 shows in side elevation and partly in section a view of an electrical overload switch constructed in accordance with the invention;

Figure 2 is a plan view of the overload switch shown on line 2—2 of Figure 1.

Referring firstly to Figure 1 of the drawings, the overload switch comprises for a three-phase electrical switch three bi-metal strips 10, 11 and 12 having end portions 13, 14 and 15 bent at right angles to form attachment lugs by means of which the strips are secured with screws 16, 17 and 18 to a base member 19 formed of a block or sheet of insulating material.

Conveniently the strips 10, 11 and 12 extend through holes 48 formed in the base member 19, and the lugs are secured within a recessed part 49 formed in the outer face of the base member 19, and the screws 16, 17 and 18 are secured within internally-threaded sleeves 50 disposed within holes formed in the base member,

2

the inner ends of these sleeves receiving overload terminal screws 51, 52, 53.

It will be understood that if the overload switch is constructed as an individual unit the base member 19 may be individual to the switch. If the switch is applied to a low-tension electrical switch of the type illustrated in Figure 2 the base member 19 may support the bi-metal strips in common with other components of the low-tension electrical switch.

The bi-metal strips are disposed side by side and parallel to each other and are spaced apart in line in the direction in which the bi-metal strips can bend.

15 Each of the strips is provided with a heating winding, such as that seen at 20, wound on an insulating former 21, which may be formed of asbestos or other suitable heat resisting material enveloping the bi-metal strip, the whole being covered by an outer insulating sheet 22, also of suitable heat resisting insulation.

The end portion of each bi-metal strip which is remote from the secured end is somewhat narrower than the remaining portions of the strip 25 so that there exists between the end portion 23 and the remaining portions of the strip a pair of shoulders 24 forming abutments for the support of an overload switch contact operating member, as will be later described.

30 In line with the bi-metal strips, and also secured to the base member 19, are provided a pair of overload switch contact supporting strips 25 and 26, the former, 25, being more or less rigid in nature so that its associated overload contact 27 can be regarded as a fixed contact, and the latter 26 being formed of a suitable resilient material, for example phosphor bronze, so that its associated overload contact 28 can be separated from the contact 27, or allowed to move towards and into contact with the contact 27, as desired.

35 Normally, the strip 26 urges the contact 28 towards the contact 27 under spring pressure, due to the resilient nature of the material from which the strip 26 is constructed.

40 The unsecured end portion of the strip 26 is engaged by the end face 29 of an overload contact operating member 30 in the form of a bar having spaced openings 31 in which engage the end portions 23 of the bi-metal strips, the bar extending lengthwise in the in-line direction in which the bi-metal strips are disposed.

45 At the other end of the bar a retaining member is provided in the form of a more or less rigid metal strip 32 of similar form to that which supports the fixed overload contact 27, one end of

the strip being secured to the base member 19 by means of a screw.

The openings 31 in the bar 30 are wider than the width of the bi-metal strips 10, 11 and 12 in the lengthwise direction of the bar, that is to say in the direction in which the bi-metal strips are adapted to bend under the influence of heat transmitted to them from their respective heating windings.

With the overload switch contacts 27 and 28 in the "made" position, as shown in Figure 1, with the end face 29 of the bar engaging the strip 26 there exists between each of the bi-metal strips and that wall of their respectively associated openings in the bar which they are adapted to engage when heated a clearance space 33 so that the temperature of any one of the bi-metal strips has to be raised to a certain value before engagement between this wall of the opening and the strip takes place, and hence before the bar is moved endwise to open the contacts 27 and 28. The engagement between these walls 34 of the openings 31 and their respective bi-metal strips thus constitutes a lost-motion connection between the strips and the bar.

The end portion 35 of the bar 30 which is of somewhat different length, as shown in Figure 1, is shorter than the end portion 36 so that the end face 37 has a different spacing from the walls 38 of the openings 31 than the corresponding spacing of the end face 29 of the walls 34. As a result it is possible to reverse the position of the bar 30 on the bi-metal strips so that the end face 37 is in operative engagement with the strip 26, and the bi-metal strips in bending under heat transmitted from their windings 28 engage the walls 38 instead of the walls 34 of their associated openings 31 in the bar.

In the preferred construction illustrated it will be apparent that the contacts of the strips 26 and 25 are secured in somewhat different positions relative to the ends of their respective strips so that they engage each other correctly. The unsecured end of each of the contact supporting strips 25 and 26 is bent over at right angles and lies parallel to the side faces of the bar 30, the two bent-over end portions of the strips being spaced apart by the thickness of the bar 30 so as to form a guide for the end of the bar which operatively engages the movable strip 26. Likewise the bent-over end 41 of the retaining member 32 serves to prevent the bar 30 becoming displaced from the bi-metal strips in any position in which the whole overload switch assembly may be held.

Individual terminal screws are provided for each winding 20 of the bi-metal strips, these terminal screws being indicated at 42, the other end of the winding being brought out to the terminal screws 51, 52 and 53 already referred to.

An outer casing 43 is provided to protect the bi-metal strips, the bar and overload contact, the casing having a peripheral flange 44 by means of which it is screwed with screws 45 to the supporting base 19.

What I claim then is:

1. An electrical overload switch for an electrical circuit having a plurality of conducting leads in each of which the presence of an overload current is required to actuate the switch, said overload switch comprising a plurality of bi-metal strips, arranged substantially parallel to each other and side by side spaced apart in line in the direction in which they are adapted to bend, supporting means for the strips, at least

one strip being associated with each of said conducting leads, said bi-metal strips being adapted to bend when subjected to temperature change, a plurality of heating windings at least one being associated with each strip and being secured in proximity to each of said strips whereby a proportion of the heat developed in the winding is transmitted to the strip, the winding associated with each strip being adapted to carry a current varying with that in each of said respectively associated conducting leads, overload switch contacts, an overload switch contact operating member comprising a bar extending lengthwise along said in-line direction of the bi-metal strips having a plurality of spaced openings one associated with each bi-metal strip into which openings a portion of each such strip extends, said openings being wider than the width of the strip in the direction in which increase of temperature causes the strips to bend, said bar being adapted to move the overload switch contacts relatively to each other in endwise movement of the bar in one direction, by engagement of an abutment on the bar with means for moving said contacts relatively, each of said strip portions being spaced from that wall of its respective bar opening towards which the strip bends when subjected to an increase in temperature, each of said strips being adapted to bend to engage said wall and move said bar in the said direction to move the switch contacts when heated by an overload current of the required value in its associated winding, and said bar being provided with an abutment at each end one such abutment having a spacing lengthwise along the bar from the walls of said openings engaged by said strips in bending different from the spacing of the other abutment from the walls of openings opposed to those aforesaid, whereby reversal of the bar to change from use of one abutment to the other results in a variable overload setting.

2. An electrical overload switch for an electrical circuit having a plurality of conducting leads in each of which the presence of an overload current is required to actuate the switch, said overload switch comprising a plurality of bi-metal strips secured upon an insulating base member, and arranged substantially parallel to each other and side by side spaced apart in line in the direction in which they are adapted to bend, at least one strip being associated with each of said conducting leads, said bi-metal strips being adapted to bend when subjected to temperature change, a heating winding wound on each strip and insulated electrically therefrom, the winding associated with each strip being adapted to carry a current varying with that in each of said respectively associated conducting leads, overload switch contacts, an overload switch contact operating member comprising a bar extending lengthwise along said in-line direction of the bi-metal strips having a plurality of spaced openings one associated with each bi-metal strip into which openings a portion of each such strip extends, said openings being wider than the width of the strip in the direction in which increase of temperature causes the strips to bend, said bar being adapted to move the overload switch contacts relatively to each other in endwise movement of the bar in one direction, each of said strip portions being spaced from that wall of its respective bar opening towards which the strip bends when subjected to an increase in temperature, each of said strips being adapted to bend to engage said wall and move said bar in the

said direction to move the switch contacts when heated by an overload current of the required value in its associated winding, the abutments on the bar being constituted by the end faces thereof which engage in operation directly against a resilient metal strip carrying one of the overload switch contacts, said resilient metal strip being secured at one end to said base member, the other of said overload switch contacts being carried by a second metal strip secured at one end to said base member and disposed substantially parallel to the other said contact-carrying strip, the unsecured end of each of said contact-carrying strips being bent over to lie parallel to side faces of the bar and constituting a guide for the end of the bar operatively engaging movable contact-carrying strips.

3. In an electrical overload switch of the kind in which, for operating a pair of overload switch contacts, there is provided, a plurality of bi-metal strips having heating windings, and arranged substantially parallel to each other side by side spaced apart in line in the direction in which they are adapted to bend on the presence of a current in their heating windings; an overload switch contact operating bar common to all said bi-metal strips, said bar having for selective insertion between the bi-metal strips and the overload switch contacts at least two sets of longitudinally spaced abutments, each set including one abutment for co-action with the overload switch contacts, and spaced from it by distances less than the normal separation between the bi-metal strips and the overload switch contacts, abutments for engagement by each strip establishing a lost motion connection between the former and the latter, the spacing between the abutment for engaging and operation the overload switch contacts and those for engagement by each strip being different in one set as compared with the other set to provide at least two overload settings.

4. In an electrical overload switch of the kind in which, for operating a pair of overload switch contacts, there is provided, a plurality of bi-

metal strips having heating windings, and arranged substantially parallel to each other side by side spaced apart in line in the direction in which they are adapted to bend on the presence of a current in their heating windings; an overload switch contact operating bar common to all said bi-metal strips, said bar having for selective insertion between the bi-metal strips and the overload switch contacts, two sets of longitudinally spaced abutments, one set including one abutment at one end of the bar for co-action with the overload switch contacts and spaced from it by distances less than the normal separation between the bi-metal strips and the overload switch contacts, abutments for engagement by each strip establishing a lost motion connection between the former and the latter, the other set including at the other end of the bar one abutment for co-action with the overload switch contacts and spaced from it by distances less than the normal separation between the bi-metal strips and the overload switch contacts but different from those pertaining to the first said set, abutments for engagement by each strip, and means supporting the bar removably in relation to the bi-metal strips and the overload switch contacts whereby it can be reversed end to end to bring into operation one or the other set of abutments.
